To all whom it may concern:

Be it known that I, Frank M. Salisbury, a citizen of the United States, residing at 66 Kenton Road, Kenmore, New York, in the county of Erie and State of New York, have invented a new, original, and ornamental Design for Airplane, of which the following is a specification, reference being had to the accompanying drawing, forming part thereof.

Fig. 1 is a side elevation of an airplane showing my novel design;

Fig. 2 is a front end elevational view thereof; and

Fig. 3 is a top plan view thereof.

I claim:

The ornamental design for airplane, as shown.

FRANK M. SALISBURY.
